(57) **CLAIM**

I claim the ornamental design for a finger grip, substantially as shown and described.

DESCRIPTION

FIG. 1 is a perspective view of a finger grip in accordance with an embodiment of the present invention;

FIG. 2 is a top view of FIG. 1;

FIG. 3 is a bottom view of FIG. 1;

FIG. 4 is a front view of FIG. 1;

FIG. 5 is a back view of FIG. 1;

FIG. 6 is a left view of FIG. 1;

FIG. 7 is a right view of FIG. 1; and,

FIG. 8 is a perspective view of the finger grip illustrated in FIG. 1 in a detached position.

The two elements of the finger grip include hook-and-loop attachment surfaces as illustrated by the surface shadings in the Figures.

1 Claim, 6 Drawing Sheets
